COLLAPSIBLE BED

Charles A. Linsley, St. Petersburg, Fla.

Application July 13, 1944, Serial No. 544,662

8 Claims. (Cl. 5—21)

1

This invention relates to bed construction, and more particularly to the provision of twin beds which may be used independently, but are capable of being nested together in order to occupy a minimum of space with one of the beds concealed.

It is an object of the invention to provide twin beds which will afford comfort to the occupants and which can use mattresses of any desired thickness so that they will be as comfortable as other ordinary beds, and which may be nested for compactness, and which may be made ready for immediate use upon a moment's notice.

It is a further object of the invention to provide twin beds which may be made up ready for use prior to their being nested and which may be separated, and the actual simple pulling apart or act of separating of the beds will cause the inner bed to automatically rise to the full height of the outer bed so that both beds may be immediately occupied.

A further object of the invention is to provide practical and substantial twin beds of the above described character of simple, durable and economical construction, and which will improve the appearance of the room in which they are used.

A further object of the invention is to provide mechanism for the collapsing of the inner bed, which may be manipulated by a lever and by applying a small amount of weight upon the same.

Further objects and advantages of my invention will be apparent from the following specification taken in conjunction with the accompanying drawings, wherein:

Figure 1 is a perspective of the beds in separated relation;

Fig. 2, a perspective of a portion of the working parts;

Fig. 3, a section through the framework of the beds in side by side relation;

Fig. 4, a bottom plan of the beds nested without the mattresses;

Fig. 5, a vertical longitudinal section of the nested beds without the mattresses;

Fig. 6, a top plan view of the nested beds without the mattresses;

Fig. 7, a longitudinal section of the inner bed supported in operative position without the mattresses and springs; and

Fig. 8, a bottom plan of the beds devoid of mattresses in side by side relation disclosing particularly the release mechanism for causing the inner bed to assume its operative height.

As shown in Fig. 1, twin beds are provided with mattresses 10 and 11, and frames 12 and 13. The

2

mattresses 10 and 11 are of conventional, preferably inner-spring, construction to afford maximum comfort to the user. The mattresses 10 and 11 may be of similar dimensions, although if desired the mattress 10 may be slightly smaller in length and width.

The frames or bases 12 and 13 are designed primarily for their supporting function, as is true of the base of any bed, but they are also designed for pleasing appearance, both when nested or when they are separated. They are likewise designed to simulate a single bed when they are in nested relation. These frames or bases are also designed to provide maximum compactness, as well as simplicity in the nesting of the same in addition to their supporting functions. The frame 13 forms a housing or outer casing for the frame 12 and its mattress. Rollers 14 are mounted within the plane of the end member of the frame 13, therefore offering no obstruction interiorly or exteriorly of this frame, and at the same time the frame can readily be rolled only in a sidewise manner. The inner bed, which includes the frame 12, has its rollers 15 mounted on the lower ends of the legs 16 at right angles to the rollers of the other bed, and therefore the inner bed can only be moved in an endwise direction. Thus, when the beds are being nested the inner bed having the frame 12 is moved endwise to position beside the other bed, having the frame 13, which forms the housing. This housing is moved laterally to bring the beds into nested relation. The inner extremities of the ends of the frame 13 are provided with bevelled felt-covered surfaces 17 in order to prevent the corners of the inner bed from being marred, and in order to cause automatic alignment by the movement of the inner bed endwise if necessary in assembling.

As shown in Fig. 1, when the beds are ready for occupancy they are of the same height. However, in order to accommodate the thick mattress 10, it is necessary for the bed which nests inside of the other to collapse sufficiently to permit this nesting to be accomplished. Therefore, the inner bed has a narrower frame 12 than that of the other or outer bed frame, and pivoted legs 16 carrying the rollers 15 at their lower extremities serve to support the bed in both its lowered and elevated positions.

The frame 12 of the inner bed is rectangular, and has two pairs of legs 16, one pair at each end. The legs of each pair are connected adjacent their lower extremities by means of a brace 18 of angle iron to make them of relatively strong,

rigid construction, and the upper extremities of said legs are likewise reinforced with cross braces 19. The legs 16 are fastened by bolts and nuts 20 to brackets 21 attached to the side members of the frame 12. These bolts form the pivots about which the legs swing. The upper extremities of the legs 16 are connected by pivots 22 with links 23, at one or both sides of the bed (only one being shown), which links at their opposite ends are provided with pivots 24 connected to the opposite extremities of a crank bar 25 pivoted at its center on a bolt 26 so that throwing or rotation of the crank bar 25 about the pivot 26, when the legs are depending in supporting position, when the bed is in elevated position, will by means of the links 23, swing the lower extremities of one pair of legs slightly away from the other pair, thereby permitting slight pressure on the bed to depress it to collapsed position.

The pivot 26 is mounted in a plate 27 countersunk inside of the bed frame 12, and a lever 28 having an operating knob on its free end is also pivotally mounted on said plate 27. The lever 28 oscillates in a slot 28' in the inner surface of the side frame of the bed. This limits the throw of the lever from the locked position of Figs. 2 and 7, clockwise only, sufficient to move the pivot 24 beyond dead center. This moves the upper ends of the pairs of legs toward each other and spreads the lower portions of said pairs of legs apart initiating collapse of the legs so that weight will cause them to move to fully collapsed position. When the free end of this lever is raised the pivot 24 is engaged thereby and the bar 25 is swung on its pivot 26, to cause the release of the legs. Weight of the bed and the application of slight pressure will cause the legs to swing apart at their bottoms to permit the bed to be lowered. The lever 28 is provided with a notch 29 for receiving one of the pivots 24, and due to the fact that the pivoted end of the lever 28 is mounted slightly eccentrically of the pivot 26, when the pivot 24 is engaged by the notch 29 the locking action will be accomplished, thereby maintaining the legs in upright position. When the bar 25 is in the position shown in Fig. 2 it is slightly beyond dead center, being limited as to further movement in a counter-clockwise direction by means of the lever 28 against which the nearer pivot 24 engages so that there can be no possible accidental collapsing of the bed. However, when the lever is swung upwardly the bar 25 is rotated beyond dead center in a clockwise direction. This movement of the levers swings the upper ends of the legs toward the center of the beds and the lower extremities of the legs away from the center of the bed and permits it to be forced downwardly. The spring 30 connects one of the links 23 to the bed frame, thus tending to maintain the connecting links 23-23 and bar 25 beyond dead center.

Spring means is provided for normally bringing the legs 16 into depending, operative, sustaining, position. Such spring means includes a main connecting spring 31, connecting the centers of the reinforcing braces 18 so that when the legs are released the spring 31 contracts to pull the lower extremities of the legs toward operative position, and in like manner springs 32, connecting the upper ends of the braces 19 and the ends of the bed, pull the upper ends of the legs toward the ends of the bed, thus assisting the spring 31. The springs 31 and 32 are of sufficient strength and under sufficient tension to overcome the weight of the bed structure and

lift the same when the legs are released when in collapsed position.

Stops 33 (Fig. 7) are adapted to be engaged by the braces 19, and thus limit the swinging of the lower extremities of the legs toward each other when the legs are in supporting position, while stops 34 are engaged on their under sides by the legs 16 when they are collapsed as shown in Fig. 5, thereby limiting the collapsing movement of the legs.

In order to fasten the legs 16 in collapsed position, swinging latches 35 on pivots 36, are pivoted to mounting bars 37 attached to the under side of the frame cross bars 38. Rollers 45, mounted on the cross bars 38, provide bearing means for the latches 35. These latches 35 have beveled toe portions 35' adapted to be engaged by the leg braces 18 so that these leg braces ride under these toe portions of the latches, and the legs are held in collapsed position. The extremities of the latches, remote from the toe portions 35' are adapted to be engaged and operated for releasing the legs to permit the bed to attain its proper elevation under the influence of the springs 31 and 32, and this operation can be accomplished manually by a kick of the toe or foot, or otherwise. Similarly the latch 35 can be operated by a lever, hereinafter described, on the other bed section. Springs 39 maintain the latches 35 in latching position.

In order to cause simultaneous release of the latches 35, links 40 are attached to opposite ends of a bar 41 pivoted in the frame at 41'. Movement of this bar in a clockwise direction (Figs. 2 and 6) will retract the latches to release the legs. Reverse movement is automatic on account of the springs 39.

The lower extremities of the beveled felt-covered surfaces 17 of the outer casing have mounted therein spring pressed detents 42, on pivots 43, under the influence of the springs 44. Each of these detents engages a section of the frame so that it can only move in a limited arc from a position substantially in alignment with the end of the frame 13 to a position at right angles thereto across the line of movement of the inner bed frame 12, and directly in the path of movement of the latches 35.

Thus when the beds are brought into nested relation the detents 42 are collapsed against the action of the springs but when they are moved in the opposite direction they trip the latches 35, just as the beds are separated and the inner bed automatically assumes its full height on the legs 16 due to the action of the springs 31 and 32. This height corresponds to that of the other bed.

The lever 28 and associated linkage locks the legs in fixed relation until the lever is swung upwardly, whereupon as previously stated the weight of the bed and slight pressure by an individual will cause the bed to assume its lowermost position, and the braces 18 connecting the legs at their lower extremities ride beneath the toe portions of the latches 35 and are held in this position until these latches are released, at the same time the springs 31 and 32 being placed under tension. Release of the latches manually or by contact with the detents 42-42 allows the springs 31 and 32 to cause the bed to assume its normal elevated position.

With the construction just described the inner bed being in elevated position, and it being desired to nest the beds the operator only raises the end of the lever 28 whereupon the weight of

the bed, together with slight pressure from an individual will cause the legs 16-16 to spread apart and the bed to lower or collapse so that it can be slid into the frame and form a snug fit with the other bed, provided it is in alignment therewith.

When the legs are being folded the rollers or casters will be swung upwardly and outwardly to a position substantially within the confines of the frame, but slightly exposed below the same so that the rollers will still be effective.

The inner bed has its sides of uniform width except adjacent its extremities where the sides are under-cut to permit the trip levers 42 to pass thereunder. The force necessary to raise the inner bed from its lowered to its raised position depends upon the weight of the bed assembly and therefore is variable or adjustable, as for example, by turnbuckles 31 or in any other desired manner.

In view of the fact that the rollers 15 are on an axis transversely of the inner bed, this inner bed can be moved endwise to bring it into proper alignment with the outer casing, thereupon the outer casing or other bed can be easily moved into nested relation with the inner bed.

The felted beveled surfaces 17 assist in the aligning of the beds.

It will be obvious to those skilled in the art that various changes may be made in the invention without departing from the spirit and scope thereof and therefore the invention is not limited by that which is shown in the drawing and described in the specification but only as indicated in the appended claims.

What is claimed is:

1. A collapsible bed assembly comprising completely separable and independent outer and inner beds nested one within the other and usable when not nested either as twin or independent beds, supporting rollers for each of said beds arranged to permit one bed to be moved endwise and the other bed to be moved laterally whereby said beds are movable into separated or nested position, legs pivotally and collapsibly mounted on said inner bed, means for normally biasing said legs toward extended position to support the bed in elevated position, said biasing means being sufficient to elevate said bed, locking means on said inner bed for maintaining said legs in collapsed position to support the bed in lowered position during nested relationship, means on said outer bed for engaging and releasing said locking means during separation of the beds to permit said biasing means to extend said legs to elevate said inner bed upon separation of said beds so that the inner bed will automatically assume its position of use.

2. In a collapsible twin bed assembly comprising a pair of nestable frames, supporting rollers for said frames, the rollers in one frame being mounted substantially at right angles to those of the other frame so that one frame is movable endwise into position to have the other frame moved laterally thereover, said inner frame having legs adjacent each end pivoted intermediate their extremities to said frame, and spring means normally biasing said legs toward extended position, the tension upon said springs being sufficient to move said legs to upright position with said frame elevated, the upper ends of said legs being connected by linkage adapted to be disposed offcenter for locking the legs extended when they support the bed in an elevated position but having a manipulating portion for mov-

ing the links to unlock the legs so that the bed may be lowered.

3. A collapsible bed assembly comprising completely separable and independent outer and inner nestable beds nested one within the other which when not nested are relatively movable and useable as independent single beds or as twin beds, supporting structure for rigidly supporting said beds, the supporting structure for the inner bed comprising spaced, rigid, leg frames pivotally mounted transversely under said inner bed, and foldable longitudinally thereof, means for locking said leg frames solidly in extended position for supporting the bed in an elevated position of use, the construction and arrangement of said supporting structure providing both lateral and longitudinal solidarity of said bed, supporting rollers for said beds arranged to permit one bed to be moved endwise and the other bed to be moved laterally whereby said beds are movable into separated or nested position, means for normally biasing said leg frames toward extended position to support the bed elevated, said biasing means being sufficient to elevate said bed, locking means on said inner bed for maintaining said legs in collapsed position to support the bed in lowered position during nested relationship, and means on said outer bed for engaging and releasing said locking means during separating movement of said beds to permit said biasing means to extend said legs to elevate said bed.

4. In a collapsible bed unit, a frame, leg members pivoted intermediate of their length to the frame, spring means connecting the inner ends of said leg members to the ends of the frame and tending to bias the inner ends of the leg members apart, spring means connecting the outer ends of said leg members and tending to bias them toward each other, all of said springs being tensioned when said legs are in collapsed position, the pivot points for said leg members being spaced from the ends of the frame so that when collapsed the outer ends of the legs will swing upwardly and outwardly to a position substantially within the confines of the frame, but protecting slightly below said frame so that the outer leg ends will still be effective to support said bed when in collapsed position.

5. A collapsible bed assembly comprising completely separable and independent outer and inner beds nested one within the other and which when not nested are relatively movable and useable as independent single beds or as twin beds, supporting structure for rigidly supporting said beds, the supporting structure for the inner bed comprising spaced, rigid, leg frames pivotally mounted transversely under said inner bed, and foldable longitudinally thereof, means for locking said leg frames solidly in extended position for supporting the bed in an elevated position of use, the construction and arrangement of said supporting structure providing both lateral and longitudinal solidarity of said bed, supporting rollers for said beds arranged to permit one bed to be moved endwise and the other bed to be moved laterally whereby said beds are movable into separated or nested position, means for normally biasing said leg frames toward extended position to support the bed in elevated position, said biasing means being sufficient to elevate said bed, locking means on said inner bed for maintaining said leg frames in collapsed position, said locking means comprising an elongated bar pivotally mounted on said inner bed having one end constructed and arranged to perform the locking

function, the opposite end being constructed and arranged to engage a portion of said outer bed upon relative movement between said beds to move said locking means to unlocked position upon separation of the beds whereby the legs of said inner bed will automatically be extended to support said inner bed in elevated position ready for use.

6. A collapsible bed assembly comprising completely separable and independent outer and inner beds nested one within the other and which when not nested are relatively movable and usable as independent single beds or as twin beds, supporting structure for rigidly supporting said beds, the supporting structure for the inner bed comprising spaced, rigid, leg frames pivotally mounted transversely under said inner bed, and foldable longitudinally thereof, means for locking said leg frames solidly in extended position for supporting the bed in an elevated position of use, the construction and arrangement of said supporting structure providing both lateral and longitudinal solidarity of said bed, supporting rollers for said beds arranged to permit one bed to be moved endwise and the other bed to be moved laterally whereby said beds are movable into separated or nested position, means for normally biasing said leg frames toward extended position to support the bed in elevated position, said biasing means being sufficient to elevate said bed, locking means on said inner bed for maintaining said leg frames in collapsed position, said locking means comprising an elongated bar pivotally mounted on said inner bed, the inner end of said bar being formed to engage a portion of said leg frames to lock said leg frames in collapsed position, cam means on the outer end of said bar, spring means normally biasing said locking means into locking position pivotally mounted abutment means on said outer bed, spring means normally biasing said abutment means into the path of movement of the cam means on said elongated bar during separating movement of said beds whereby upon separation of the beds said abutment means will cause said locking means to move to unlocked position thus permitting extension of the legs on said inner bed and the elevation of said inner bed to a position ready for use, said abutment means being movable against the action of said spring means and out of the path of movement of said cam means during relative movement of said beds into nested relationship.

7. A collapsible bed assembly comprising completely separable and independent outer and inner nestable beds nested one within the other and usable when not nested either as twin or independent beds, supporting rollers for said outer

5 bed, legs pivotally and collapsibly mounted intermediate their extremities adjacent the ends of and on said inner bed, supporting rollers mounted on the outer ends of said legs, means for normally biasing said legs toward extended position to support the bed in elevated position, said biasing means being sufficient to elevate said bed, locking means on said inner bed for maintaining said legs in collapsed position to support the bed in lowered position during nested relationship, means on said outer bed for engaging and releasing said locking means during separation of the beds to permit said biasing means to extend said legs to elevate said inner bed upon separation of said beds so that the inner bed will automatically assume its position of use, and leg swinging linkage for simultaneously swinging said legs from extended position toward collapsed position.

8. A collapsible bed assembly comprising completely separable and independent outer and inner beds nested one within the other and usable when not nested either as twin or independent beds, supporting rollers for each of said beds, legs pivotally and collapsibly mounted on said inner bed, means for normally biasing said legs toward extended position to support said inner bed in elevated position, said biasing means being sufficient to elevate said inner bed, locking means on said inner bed for maintaining said legs in collapsed position to support said inner bed in lowered position during nested relationship, means on said outer bed for engaging and releasing said locking means during separation of the beds to permit said biasing means to extend said legs to elevate said inner bed upon separation of said beds so that the inner bed will automatically assume its position of use, means comprising a crank bar rotatable beyond dead center for locking said legs in extended position for supporting said inner bed fully elevated, and means comprising an operating hand lever for unlocking said last mentioned means and for swinging said legs apart to permit said inner bed to be lowered.
